UNITED STATES PATENT OFFICE.

RUDOLPH F. STEHLIK, OF CHICAGO, ILLINOIS, ASSIGNOR TO RESERVE HOLDING COMPANY, OF KANSAS CITY, MISSOURI, A CORPORATION OF DELAWARE.

AUTOMATIC TELEPHONE SYSTEM.

Application filed May 23, 1927. Serial No. 193,432.

This invention relates in general to automatic telephone systems, but is more particularly concerned with such systems in which line finders are employed to connect an idle selector switch with a calling line, and the principal object of the invention, briefly stated, is the production of a new and improved finder switch system, the improvements tending to make the system more reliable in its operation as well as cheaper to install and maintain.

Heretofore finder switch systems have been devised along two general plans, the one employing a common control mechanism which directly sets the wipers of the finder switch upon the contacts of a calling line. The other employed finders of the so called selective type, that is the finder switch is moved either under its own control or under the control of a common equipment, and as it moves it individually tests each contact over which its wipers pass, in search of particularly marked contacts designating a calling line. If the finder switches are of a two motion Strowger switch type, whose wipers are moved first in a vertical direction to find the level containing the contacts of the calling line, and then in a horizontal direction to engage the particular contact set of the calling line, both these finder systems have their advantages and their disadvantages. In adaptations of this kind, the directive principal of operation is particularly advantageous in moving the wipers of the finder switch in the first or vertical direction, and the selective plan of operation is particularly advantageous in moving the wipers in a second or horizontal direction.

Accordingly as a further object of this invention, I provide a finder switch system employing directive movement of the finders in an initial direction and selective movement of the finders in a secondary direction, to produce a finder switch system materially simpler than either of the systems mentioned heretofore.

The Strowger switch, which I incorporate in one embodiment of my invention, is primarily a one hundred point switch, whose wipers are moved in ten vertical steps each selecting a level, and then in ten horizontal

steps to contacts in the selected level to select one of the one hundred lines in the basic groups served by the switch. Finder switch practice employed heretofore has brought out certain advantages in increasing the number of lines over whose contacts one finder switch sweeps, that is by increasing the line capacity of the finder from one basic hundred lines group to two hundred basic groups, certain advantages in trunking and certain economies in equipment are realized. By equipping the Strowger switch with two sets of wipers, I am able to double the capacity of the finder, arranging it so that after the wipers have been elevated to a desired level, tests are made on the two sets of contacts in that level, that is lines of the second hundred line basic groups are tested simultaneously.

Accordingly as a further object of my invention I provide a finder switch system of the two hundred line capacity, in which system I provide simultaneous hunting in a level of each of the two hundred line groups served by the finder.

To be eminently successful a finder switch system must operate quickly, to reduce the length of time elapsing between the removal of the receiver by a calling subscriber and the reception of dial-tone by him, to indicate that the switch mechanisms are in proper position to receive the directive digits of his call. If a finder switch moves in a vertical direction first and then in a rotary direction, a considerable amount of time is required to reach the contacts of a line whose finder bank designation is of a high order, that is lines in the 60, 70, 80, 90 and 0 groups. If line 95 for example is the calling line, the finder switch of the systems devised heretofore would be required to take ten vertical steps, followed by five steps in a horizontal direction. The time required for such operation would be relatively long. However if line 25 happens to be the calling line, the finder switch is required to take only two steps in a vertical direction followed by five steps in a horizontal direction and the time required for this operation is relatively short. From the foregoing it will be apparent that the calls to all of the lines in the

first five tens groups of the switch can be made in a sufficiently short interval of time, while the calls from all of the lines in the upper five tens groups of the bank, that is 5 groups 6 to 10 inclusive, require a relatively long period of time. To remedy this condition, I employ a system of preferential service, in which the lines in the first five tens groups of each of the one hundred line 10 basic groups handled by the finder are grouped together and handled by one group of finders, thru a control equipment common to that finder group. The lines of the second five tens groups of both of the hundred line basic groups are grouped together and handled by a second group of finder switches, in which latter finder switches, tens 15 groups #6 appears as level #1, tens group #7 as level #2, and tens group #10 as level #5. By this arrangement I have provided, 20 a finder switch system in which no finder switch is required to take more than five vertical steps in the normal course of events to reach the level containing the contacts of 25 a calling line. However, in order to provide for emergency service, each finder switch of the group has access to the entire two hundred lines, the tens groups containing 30 these lines occurring in regular consecutive order in the banks of the first finder switch group, and in reverse order in the banks of the second finder switch groups, that is tens groups 6 to 10 appear as 1 to 5 inclusive in said second group, tens group 1 35 appears as level 6, 2 as 7, 3 as 8, and 5 as 10. By this arrangement each finder switch has access to the entire two hundred line group, but serves only the one hundred lines appearing 40 in the particular group of levels to which it has first choice in the normal working of the system, and serving lines in the other group by taking more than five vertical steps when the traffic in the group is heavy or when an emergency arises. By this system 45 of preferential service which I employ as a further object of my invention, I am able to materially speed up service by reducing the average time required to elapse before the calling subscriber hears the dial tone which tells him that the switch mechanism 50 is in readiness for his directive impulses.

The drawings comprising Figs. 1 to 4 inclusive when arranged with Figs. 2, 3, and 4, 55 and to end in a line, with Fig. 1 above Fig. 3, with correspondingly numbered lines in alignment, show sufficient details to enable a clear understanding of my invention.

In Fig. 1, I show calling lines A and B, 60 which are assumed to be corresponding lines in each of the one hundred line groups served by the finder switch. That is line B is assumed to be line number 115 and line A 215, in which case the contacts of the 65 two lines will be simultaneously engaged by

the switch wipers. In Fig. 1 I also show the finder switch F which is a two motion switch of the Strowger type, whose wipers are moved first in a vertical direction to select the level contained in the contacts 70 of the calling line, and then in a rotary direction to pick out the particular set of contacts in that level, which are associated with the calling line. The finder switch F is directly connected to the selector switch 75 S which is of the usual Strowger switch type, whose wipers are moved first in a vertical direction under the control of the calling device of the subscriber's station, and then automatically in a horizontal direction 80 to select an idle trunk in the selected level.

In Fig. 3, I show the finder allotter FA1 and the control equipment CE1 through which the finder switches of the group containing the finder F are selected and controlled. The finder allotter FA1 is mechanically like the well known rotary lineswitch, whose wipers have no normal position and move in one direction only, the mechanism being arranged to move the wipers when the 90 magnet of the switch deenergizes.

In Fig. 2 I show the level relay group comprising relays 201 to 205, which relays are controlled by the start wire leading from the lines of the respective tens groups, to 95 mark the designation of a calling line in the banks of the vertical sending switch. In Fig. 2 I also show the sending switches S1 and S2, S1 being associated with the control equipment E1 of Fig. 3 to assist that 100 equipment in controlling the finder switches of the #1 group. Vertical counting switch S2 is associated with the control equipment CE2, of Fig. 4 to assist that equipment in controlling the switches of the second finder group. In Fig. 2 I also show the lever relays 206 to 210, which are controlled over the start wires leading from the sixth to the tenth tens groups of lines being energized over those start wires, so mark the designation 105 of a calling one of these lines in the banks of the sending switch YS2. It will be noted in Fig. 3 that when the relay 201 is energized responsive to a call started by a line in the first tens group, that is the line 110 215 for example, that line is marked calling in the banks of VS1 and VS2 being marked as the first contact over which the wiper 221 115 of VS1 rotates and being marked as the sixth contact over which wiper 225 of VS2 rotates. Similarly it will be noted that the 120 energization of relay 206 responsive to the initiation of a call by a line in the sixth tens group of lines, will be marked as the first contact in the banks over which wiper 224 125 of the vertical sending switch VS2 moves, and will also be marked as the sixth contact in the bank over which wiper 220 of the counting switch YS1 rotates.

By this arrangement it will be seen that the first five 130

tens groups are first choice levels to the switch VS1, and the second five tens group, that is groups 6 to 10 inclusive, are first choice to the switch VS2. The purpose of this will be more fully brought out hereinafter.

In Fig. 4, I show finder allotter FA2 and the control equipment CE2, which is a duplicate of the equipment shown in Fig. 3. The equipment CE2 controls finders of the group 2 which are pre-selected by the finder allotter FA2. The finders of group 2, being duplicates of the finder F, are not shown in the drawing. Group 2 finders have access as first choice to tens groups 6 to 10, and as second choice to tens groups 1 to 5, and are normally operated in response to a call in anyone of the tens groups 6 to 10.

Throughout the drawings I have shown a plurality of batteries, to avoid an unnecessary complication of the figures. In an installation of the system of my invention, there would be but one battery, preferably with its positive pole grounded.

Assume now that the line A initiates the call, line relay 2 is energized over the loop circuit, sending a ground over the start wire 64 to energize the level relay 201, to mark the first level calling in the banks of VS1. Energization of level relay 201 places a ground on the group 1 start conductor 277, starting the control equipment CE1 into operation. Finder allotter FA1 having previously preselected the finder F, that finder is now started by the control equipment CE1 and takes one vertical step, at which time the vertical sending switch VS1 encounters the marked contact to bring the finder to rest. The control equipment CE1 is arranged to operate upon revertive pulse from the finder F, that is CE closes an impulsing circuit to the magnet of the finder that circuit being branched off to include the magnet of the counting switch CS1. When the finder magnet has fully energized, it closes a circuit to send back a pulse to energize a pulse terminating relay, which upon energizing opens the circuit both to the finder magnet and to the counting switch magnet. When the pulse terminating relay is energized, circuit is completed from the marked contact encountered by the switch CS1, to the change over relay, which energizes and locks. The energization of the switch over relay changes the impulsing circuit from the vertical to the rotary magnet of the finder switch F, so that as soon as the pulse terminating relay falls back, an impulse is sent to the rotary magnet. By this arrangement there is no pause between the vertical and rotary impulse series. Revertive control is exercised from the rotary magnet the same as from the vertical magnet. The rotary magnet continues to energize until the private wiper 54 of the finder

F encounters battery potential, which potential marks the line as calling, at which time, switch through relay 302 of the control equipment CE1 is energized, pulsing ends, switching relay of the finder F is energized, 70 and the calling line is seized by the finder F and made busy.

Control equipment CE1 is released by the energization of the switch through relay, and returns to normal under its own control. 75 During the interval required for CE1 to return to normal, start conductor 277 is extended into control equipment CE2 so that in case a call is waiting in the group 1, that is a call from one of the first five tens levels, 80 that call can be immediately handled by group 2 provided that the latter equipment is idle at the moment. Counting switch CS1 moves to its normal position under control of a local circuit, stopping when the home 85 position is reached. When the control equipment gets to normal, finder allotter FA1 is started to search for the next idle finder of the group, which is preselected and connected with the control equipment CE1 preparatory to handling the next call.

Similarly a call initiated in a line of the second group, that is in tens groups 6 to 10, energizes the corresponding level relay over start conductors, not shown, to ground group 95 2 start conductor 371, to start control equipment CE2 in operation. The idle finder, not shown, which finder allotter FA2 has pre-selected, is started, being operated in a manner identical with that pointed out in connection with finder F. Group 2 finders controlled by equipment CE2 and counting switch VS2 have normal access to tens groups 6 to 10, those levels appearing as levels 1 to 5 respectively in the banks of the 100 finders. The finder takes the required number of vertical steps, whereupon switchover relay 406 is energized and the finder caused to move in a rotary direction under the control of its private wiper. When the calling 105 line has been reached, the control equipment is released, the finder is switched through, and the start conductor 371 is extended back through springs 436 and 425 to the relay 309 of the control equipment CE1, so that in 110 case another call is waiting in group 2, that call can be instantly handled by group 1 115 provided there are no group 1 calls waiting at the instant.

Returning now to the operation of finder 120 F, it will be noted that there are two switching relays 5 and 6, and that ground on conductor 71 is projected to the lower terminals of both of the upper windings of these relays. The other terminals of these windings 125 are terminated on wipers 54 and 51 respectively, those two wipers engaging the private contacts in the selected level. Should either of these private contacts be at battery potential, corresponding finder switching relay 130

- will be energized, the switch through relay of the control equipment CE1 will be energized, and the finder will stop upon the contact set. In other words, wipers 51 and 54 simultaneously hunt in the two groups of lines. If for example lines A and B would initiate a call simultaneously, or line A should initiate a call slightly ahead of line B, finder equipment CE1 would be started by a call initiated by line A. When the wipers 51 and 54 encounter the contacts associated with lines A and B, circuits should be completed for both relays 5 and 6, one or the other of these relays would pull up first. 15 No special adjustment is required to cause this action, as it is impossible to construct two relays exactly alike in time constant, as would be necessary if both relays 5 and 6 were to completely energize simultaneously. 20 Assume the line 5 pulled up first, line A would get the call, line B would maintain a ground on the start wire 64, start relay 201 would be energized, and when the control equipment CE1 switched through, the call pending on line B would be handled by control equipment CE2, if idle. 25

When the control equipment CE1 is started responsive to a ground upon a start conductor 277, the selector S is seized by ground on conductor 67 projected from the control equipment CE1. Line relay 7 of selector S is energized, and closes the well known circuit for the release relay 8, which energizes and at spring 47 extends ground back on release conductor 68. Therefore when switching relay 5 or 6 of the finder is energized, it locks to the release trunk conductor through its lower winding independent of its energizing circuit, and is maintained in energized position as long as the release trunk conductor is grounded. 40

In case the finder switch F happens to be the last idle finder in the group, when it is seized and the selector associated with it energized, ground is removed from the busy common conductor 70, whereupon all finders busy relay 306 of the control equipment CE1 is energized, and the start conductor 277 extended to the control equipment CE2, to enable that equipment to handle calls originating in group 1. 45

Having thus described my invention in general I will now proceed with a detailed description of its operation. 50

55 Line A calling.

Assume now that line A initiates the call, by removing the receiver from the switch hook. A circuit for line relay 2 is then closed from ground through springs 22, line conductor 60, the impulse springs, transmitter, receiver, and switch hook, of the calling station A to the line conductor 61, springs 20, through the winding of line relay 2 to battery. Line relay 2 energizes over this

circuit and at springs 23 prepares a point in the circuit of cut-off relay 1, by connecting the upper winding of that relay through the conductor 76 to the private contact 76' in the finder switch bank. Thus the energization of line relay 2 places battery potential upon the contact 76', to make the line calling. Energization of line relay 2 at springs 24 closes a circuit for the level marking relay 201 traceable over conductor 64 through the winding of relay 201 to battery. Relay 201 energizes over this circuit, and at springs 230 places a ground on the group 1 start conductor 277. At springs 231, relay 201 disconnects conductor 261 from conductor 260 and connects it to conductor 265, for a purpose which will be apparent hereinafter. 70 75 80 85

Starting equipment CE1.

Ground placed upon start conductor 277 by relay 201 traverses a circuit from that conductor through springs 349 and its break contact, spring 355 and its break contact, conductor 374, springs 426, conductor 376, through the winding of start relay 308 to battery. Start relay 308 energizes over this circuit, preparing the equipment CE1 to handle the call from the #1 group line A. Energization of relay 308 closes a circuit from grounded conductor 377 through spring 353 through springs 351 through the winding of slow acting relay 301 to battery, energizing that relay which at springs 326 locks itself and relay 308 in energized position over a circuit traceable from ground through springs 326, conductor 391, thence through springs 351 conductor 392, the winding of relay 301 to battery, and through springs 353, and the winding of relay 308 to battery. The energization of relay 301 at springs 324 opens a point in the circuit of the motor magnet 310 of the finder allotter FA1, to prevent that magnet from energizing at this time. At springs 325, relay 301 closes a circuit for the upper winding of line relay 7 of the selector S, traceable from ground through springs 325, wiper 321, now associated with contacts terminating conductor 67, through that conductor, through the upper winding of relay 7 to battery, relay 7 energizing over this circuit to close the obvious circuit for relay 8, which energizes and at springs 47 places a ground upon the release trunk conductor 68, to mark the selector busy and for other purposes which will be hereinafter explained. Relay 301 at springs 327 and its break contact opens a point in the circuit of the upper winding of all finders busy relay 306 to prevent that relay energizing at this time. 100 105 110 115 120 125

Vertical impulsing.

Energization of relay 301, at spring 327 and its make contact closes a circuit for the vertical magnet 9 of the finder F, traceable 130

from ground through that spring, through the normally closed springs controlled by armature 330, spring 333 in its break contact, spring 339 and its break contact, conductor 274, through the winding of magnet 211 of VS1 to battery, with a parallel branch through conductor 393, spring 359 and its make contact, conductor 272, wiper 221 now in engagement with its first bank 10 contact, conductor 260, contacts 1 to 7 of the bank over which wiper 225 sweeps conductor 378, springs 357, conductor 394, springs 336, springs 331, wiper 322 now in engagement with conductor 372, 15 through that conductor, through the winding of vertical magnet 9 to battery. Magnet 211 of the vertical counting switch VS1 energizes over this circuit, and prepares to advance the wipers 220 to 223 inclusive 20 one step, the advance taking place when the magnet deenergizes. Vertical magnet 9 of the finder F energizes, and raises the wipers 50 to 55 inclusive of the finder F, one vertical step. The energization of relay 301 of 25 the control equipment CE1 also closes a circuit through winding of magnet 305, over a circuit traceable from ground on springs 327, normally closed contacts controlled by armature 330, springs 334, through the 30 winding of the magnet 305 to battery. Relay 305, being slow to pull up, does not attract its armature immediately. The energization of the vertical magnet 9, in addition to advancing the wipers one vertical 35 step, closes the revertive pulse circuit traceable from ground through springs 36, conductor 77, through the upper winding of relay 303 to battery, energizing the relay 303 which at springs 333 opens the circuit just traced for magnet 211 of the counting switch VS1, and at springs 331 opens the circuit just traced for the vertical magnet 9, and at springs 334 opens the circuit for the slow to pull up relay 305. The 40 de-energization of magnet 211 advances wipers 220 to 223 inclusive one step, the de-energization of vertical magnet 9 opens a circuit for relay 303 at springs 36. Inasmuch as the instant call is from a line terminating in the 45 first level of the bank of the finder of F, only one vertical impulse is required, and switch over to rotary occurs at this time. However if more than one vertical impulse is required, the foregoing circuits would again be completed, the vertical magnet being energized through wiper 221 now in engagement with its second bank contact, conductor 261, through the spring 231 and its break contact, of the first level vertical marking relay 50 201, to conductor 260, and thence over the previously traced circuit to the magnet. This impulsing would continue until wiper 221 encountered the contact whose circuit to conductor 260 was broken by the lowermost 55 springs of one of the vertical marking re-

lays 201 to 205 inclusive, at which time the change over to rotary would occur.

Change over to rotary impulsing.

Returning now to the call in progress, when the magnet 211 has advanced its wipers into engagement with their second set of contacts, wiper 221 encounters conductor 261, which is connected to conductor 265 by springs 231 of energized first level 70 relay 201. A ground now placed on conductor 272, as previously explained, extends over a circuit through wiper 221, conductor 261, springs 231, conductor 265, conductor 380, springs 358, conductor 395, springs 338, through the upper winding of relay 304, the upper winding of relay 303 to battery. Relays 304 and 303 energize over this circuit, the former locking itself through its lower winding and springs 337 through ground through spring 327 and its make contact. Relay 304, at spring 339 and its break contact opens a point in the circuit of the motor magnet 211 of the vertical 75 counting switch S1, to prevent further energization of that magnet at this time, and at spring 339 and its make contact extends the circuit to the rotary magnet 10 of the finder F, to energize that magnet to position the wipers of the finder F upon the calling contacts in the selected level. At springs 338, relay 304 opens the initial energizing circuit for itself and relay 303, permitting relay 303 to fall back. Relay 304, spring 336 80 opens a point in the circuit of the vertical magnet 9 of the finder F, to prevent further energization of that magnet at this time. The energization of relay 304, at springs 340 closes a restoring circuit for the vertical 85 counting switch CS1, traceable from ground through springs 340, conductor 275, multiple contacts of the bank over which wiper 223 sweep, wiper 223, spring 248 and its break contact through the winding of the magnet 211 to battery. The magnet 211 energizes over this circuit and at springs 248 opens its own circuit, whereupon the armature falls back and advances the wipers 220 to 223, inclusive, one step, and the springs 248 reclose the circuit of the magnet. Magnet 211 therefore operates in a buzzer like fashion advancing the wipers until wiper 223 engages its normal position contact, which is not connected to the multiple with the remainder of the contacts. Relay 303 90 upon energizing at springs 331 opens a further point in the vertical magnet circuit; at springs 332 closes a point in the testing circuit through which the rotary impulsing of the finder F will be subsequently controlled; at spring 333 opens a point in the energizing circuit of the magnet 211 of the vertical counting switch CS1, the same point being subsequently included in the circuit of the rotary magnet 10 of the finder F, to 95 100

prevent that magnet from energizing prior to the restoration of the relay 303. At the springs 334, relay 303 opens the circuit of relay 305, and permits that relay to restore as before.

Rotary impulsing.

Relay 303 restores immediately upon the opening of the circuit through springs 338, 10 closing the circuit to the rotary magnet traceable from ground through spring 327 and its make contact, normally closes springs controlled by armature 330, springs 333, spring 339 and its make contact, wiper 323 15 now engaging conductor 73, through the winding of rotary magnet 10 to battery, energizing that magnet which advances the wipers 50 to 55 inclusive of the finder F onto the first bank contact of the first level. 20 Magnet 10 upon energizing closes at spring 37 a circuit for the pulse terminating relay 303, which energizes and at springs 33 opens a point in the circuit of the magnet 10, permitting that magnet to fall back in readiness 25 for another pulse. The circuit to slow to pull up relay 305 is closed through springs 334, when relay 303 deenergizes, as before, but in the normal working of the systems the rotary magnet 10 energizes before the 30 relay 305 has had time to pull up, so the closing of that circuit is without particular effect at this time. When the wipers 50 to 55 inclusive are advanced into engagement with the first bank contact, wipers 51 and 35 54 engage the private contacts associated with the first line in the first level, however since that line is assumed to be in an un-calling position at this time, no potential will be present upon the private contacts 40 and no circuits will be completed through the wipers. Impulsing therefore continues when relay 303 restores, the cycle of operation continuing through five impulses at which time wipers 50 to 55 inclusive are in 45 engagement with the fifth contact set in the first level, the contact set containing the terminals of the line A, which is at this time assumed to be the calling line.

Switching through the finder and control equipment.

Each time the impulse relay 303 is energized, the testing circuit is projected from grounded spring 327 through the normally closed contacts controlled by armature 330, spring 332, through the lower winding of impulse relay 303, lower winding of switch through relay 302, conductor 386, wiper 320 now in engagement with conductor 71, 55 through the upper winding of relay 5, through springs 46, to the wiper 54, with a parallel path from conductor 71 through the upper winding of the relay 6 through springs 31 to wiper 51. When wipers 51 60 and 54 encounter the contacts of a calling

line, they find battery potential thereon, completing the circuit for their respective relays and relays 302 and 303 of the control equipment, energizing those relays to switch through the finder and control equipment. 70 Since line A is calling, and wiper 54 is now assumed to be in connection with contact 76' associated therewith, the circuit for relay 5 will be completed through wiper 54 and that contact, conductor 76, springs 23, 75 upper winding of cut off relay 1 to battery. Cut off relay 1, switch through relay 5, switch through relay 302, pulse terminating relay 303 are all energized or maintained energized over this circuit. Relay 5 upon energizing locks itself through its lower winding and contact 34 to the grounded release trunk conductor 68, that conductor being grounded by the release relay 8 of the selector switch S as has been hereinbefore explained. Relay 5 at springs 45 connects the negative trunk conductor 67 through the wiper 53 to the negative line 61, and at springs 43 connects the positive trunk conductor 69 through wiper 55 to positive line 60. At springs 33 and 34, relay 5 connects a release trunk conductor 68 to the wiper 54, contact 76', conductor 76 through the upper winding of relay 1 to battery, locking that relay in its energized position independent of the ground on springs 327 through which it was initially energized. The energization of relay 1 at springs 20 and 22 clears the calling line A of attachments, so that that line now extends from ground through the lower winding of the line relay 7 of the selector S over conductor 69 through the finder, line 60, calling telephone A, line 61, through the finder, to conductor 67 through the upper winding of line 100 relay 7 to battery, there being no attachments or bridges across the line either in the line equipment or in the finder. Dial tone is audible to the calling subscriber, being applied through the ground side of the 105 relay 7, by the dial tone generator, not shown, to apprise the calling subscriber at A of the fact that the switches are now in readiness to receive the directive digits which he produces with his calling device. 110

Returning now to the control equipment CE1, the energization of switch through relay 302 as hereinbefore explained, closes that spring 328 a circuit for the magnet 310 of the finder allotter FA1, that circuit including conductor 390, springs 346, springs 348 and the magnet winding energizing that magnet to advancing the wipers 320 etc., of the finder allotter onto the next contact. Energization of relay 302 at springs 120 329 closes a locking circuit for itself, through those springs and springs 327 to ground, and at springs 330 relay 302 opens a point in the impulsing circuit, to prevent further operation of the motor magnets at 125 331. 130

this time. Ground projected onto conductor 390 by springs 328, traverses the upper winding of the relay 307 to battery, energizing that relay which at springs 351 opens the locking circuit of relay 301, permitting that relay to deenergize. Relay 301 being slow to release, remains in its energized position for a definite interval after the circuit through its coil has been opened. Relay 307 upon energizing at springs 363 closes a circuit from the lower winding of relay 307 to conductor 276 through multiplied contacts over which wiper 222 of the vertical stepping switch VS1 rotates. In the event that the vertical switch VS1 has not as yet arrived at its normal or home position, relay 307 will be locked in energized position, pending the return to normal of the switch VS1. In the normal operation of systems in a call of the character just described, VS1 will be in its normal position prior to the energization of relay 307, and it is only in the case of an emergency that this locking circuit will come into play. Relay 307 upon energizing extends the start wire conductor 277 through springs 349 to relay 401 of the control equipment CE2, for a purpose which will be hereinafter explained. At springs 350, relay 307 opens a point in the circuit of relay 309, to prevent the energization of that relay at this time should there be a call pending in the second line group. At springs 364 relay 307 places another ground on conductor 275, to insure that magnet 211 of the switch VS1 will receive a supply of ground if it is not as yet in its normal position.

Relay 301 whose circuit was opened as explained before, restores after an interval, at springs 326 opens the circuit of relay 308, permitting that relay to restore to normal. At springs 327, relay 301 opens the locking circuit of relay 302, and the locking circuit of the switch over relay 304, permitting those relays to restore to normal to prepare the control equipment for handling another call. The restoration of relay 301, at springs 324 closes a circuit from the test wiper 347 of the finder allotter FA1 to the magnet through the interrupter springs 348, preparing that magnet for automatic selection of the next idle finder of the group. If the next finder switch, upon whose contacts the wipers of the finder allotter are now standing happens to be busy, ground from release trunk conductor 68 will be projected through off normal springs 45 and its break contact to conductor 75, or if the finder switch is in its off normal position, ground will be put on conductor 75 by the off normal spring 45 and its make contact, and in either event wiper 347 will encounter ground to complete the circuit through springs 345, springs 324, conductor 388, springs 348, winding of magnet 310 to battery, energizing

that magnet which interrupts its own circuit at springs 348 to permit its armature to fall back and advance the wipers of the finder allotter FA1 one step onto the next trunk. Magnet 310 upon falling back, closes its circuit at 348, and if wiper 347 is then standing on a grounded contact, magnet 310 will be again energized to advance the wipers another step. This magnet therefore operates in a buzzer-like fashion as long as the wiper 347 encounters grounded contact, coming to rest upon the first ungrounded contact which is associated with the first idle finder of the group. When the finder allotter FA1 finds the next idle finder of the group, control equipment CE1 is in readiness to handle the next call which may be placed upon it. During the interval of wiper 347 is engaging grounded contacts, relay 307 is maintained energized from the grounds pulsed up by wiper 347, over a circuit extending through spring 345, spring 324, spring 346 and its break contact through the upper winding of relay 307 to battery. Thus relay 307 is energized to open, at springs 350, the circuit of relay 309, and at springs 349, the circuit of relay 308, to prevent the starting of a call in the control equipment CE1 prior to the time that the finder allotter has preselected an idle finder.

95

A call in the second group.

Assume now that a line in the second group initiates the call, and assume further that line is in the seventh tens group. The line relay of that line will place ground on the seventh start conductor, not shown, to energize level relay 207. Relay 207 upon energizing at springs 242 grounds the group 2 start conductor 271, the circuit extending through spring 436 and its break contact, 425 and its break contact, conductor 372, springs 354, conductor 373, through the winding of start relays 402 to battery, energizing that relay to prepare the control equipment CE2 to handle the call. Start relay 402 locks itself through springs 429 to the grounded springs 470, start wire ground being first projected through springs 429 to energize the auxiliary start relay 409 over the circuit including springs 438. The energization of relays 402 and 409 prepare control equipment CE2 to handle the call, that equipment having control of a finder of the second group through the finder allotter FA2. Since the finders of the second group are duplicates to those shown in Fig. 1, at F, they are not included in order to prevent an unnecessary complication of the drawings. Returning now to the energization of relay 207, springs 241 break the connection between conductors 270 and 269, thereby preparing circuits through which the vertical counting switch CS2 will terminate the vertical impulsion after two impulses have been 130

95

sent. It will be remembered that the seventh tens group lines appear in the second level of the finders of group 2, therefore in order to reach these lines those finders must take **5** two vertical steps.

Vertical pulsing.

Energization of the auxiliary start relay 409 at springs 471 closes the inimpulsing circuit, which is traceable through the normally closed springs controlled by armature 468, conductor 473, springs 435, conductor 381, wiper 224 of counting switch CS2, conductor 271 which is engaged by that wiper, conductor 377, springs 433, conductor 474, springs 456, wiper 422 of the finder allotter and thence through the vertical magnet of the finder switch. A parallel path extends from the normally closed springs controlled by armature 468, through springs 465 to the auxiliary impulse relay 405 to battery and another parallel path through spring 464, spring 459 and its break contact, conductor 385, through the winding of the stepping magnet 212 of the counting switch CS2, to battery. The vertical magnet of the finder and the magnet 212 of the counting switch CS2, are energized over these circuits, and the auxiliary impulse relay 405, being slow to pull up is not energized in the normal working of the system. When the vertical magnet of the finder has been fully operated, a retractive pulse is returned over pulse conductor 476, closing its circuit through the upper winding of impulse relay 407 to battery, energizing that relay, which at springs 464, 465 and 462 open the various impulsive circuits just traced. Counting switch CS2, and the finder take one step, **40** magnet of the finder falling back to remove the ground from the conductor 476 to permit the impulse relay 407 to restore, whereupon the impulsive circuit is again closed and the finder and the counting switch VS2 take another step.

Last vertical impulse.

Since the calling line is assumed to be in the seventh tens group, which appears as the **5** second level in the second group of finders, two vertical impulses are all that are required, and when the counting switch VS2 takes its second step, circuit for the switch over relay 406 of the control equipment CE2 is closed, that circuit being traceable from the impulsive ground on conductor 473, springs 435, conductor 381, wiper 224 of counting switch CS2, that wiper now being in engagement with its third bank contact through which conductor 269 is connected, to spring 241 its make contact, conductor 379, springs 434, springs 458, through the upper winding of switch over relay 206, through the upper winding of impulse relay **60** 407 to battery. Switch over relay 406 and

impulse relay 407 are energized over this circuit, relay 406 locking itself in its energized position to springs 457 and its lower winding to ground through springs 471, and at springs 458 opening the initial energizing **70** circuit to permit the impulsive relay 407 to restore to start the rotary pulsing.

Rotary impulsive.

Finder group 2 is now impulsive over circuits from ground through spring 471 and its make contact, normally closed springs controlled by armature 468, springs 464, spring 459 and its make contact, through wiper 421 of the finder allotter FA2 and **75** thence through the winding of the rotary magnet to battery. Rotary magnet energizes, places ground upon retractive pulse conductor 476 to energize the impulsive relay 407 which at springs 464 interrupts the **80** magnet circuit and at springs 463 prepares a testing circuit, when the wipers of the finder are resting upon the contacts of the calling line, battery potential placed on the private contacts to the upper winding of the **85** cut off relay picks up a private wiper to complete a circuit to conductor leading to wiper 424 of the finder allotter FA2, thence through the lower winding of switch **90** through relay 408, the lower winding of impulse relay 407, springs 463 through the normally closed springs controlled by armature 468 through springs 471 and its make contact to ground, energizing the cut off relay, the switch through relay 408 and the **95** impulse relay 407 in the manner similar to that which has been hereinbefore explained. Energization of switch through relay 408 of the control equipment CE2, closes circuits to **100** return that control equipment to normal, those circuits being duplicates to the one explained in connection with the control equipment CE1 and will not be repeated at this time.

All finders busy condition.

As has been explained hereinbefore, as long as there is an idle finder in group 1, busy common conductor **105** 70 is maintained grounded, to maintain a short circuit upon the upper winding of group busy relay 306 to prevent that relay energizing. Similarly as long as there is an idle finder in group 2, busy common conductor 477 is grounded, to maintain a short circuit upon the upper **110** winding of group busy relay 404 to prevent its energization. In the event one or the other of these group busy commons becomes ungrounded due to the taking for use of the last idle finder of the group, the corresponding group busy relay is energized, and the start circuits are altered so that a call originated in the group whose finders are all **115** busy will be handled by the other group of finders, provided there are no calls in prog- **120** **125** **130**

ress in that group at the time. Assume now that the group 1 finders become busy, conductor 77 will lose its ground and when the auxiliary start relay 301 deenergizes a circuit will be completed from ground on springs 327 and its break contact, through the upper winding of group busy relay 306, through resistance 342 to battery, energizing that relay which at spring 346 and its 10 make contact closes a circuit from ground through the upper winding of relay 307 to battery, energizing the latter relay to change over the start circuit. Group #1 start conductor 277 is now extended through spring 349 and its make contact to conductor 375, thence through break contacts 437 and 428, through the winding of relay 401 to battery. If a call is originated in group 1 while no calls are in progress in group 2, the ground 20 on the start conductor will energize relay 401 to prepare the group 2 control equipment CE2 for handling the call. Relay 401, through springs 427 closes the circuit of the auxiliary start relay 409, which energizes 25 and locks the two relays in energized positions from ground on spring 407, as before. The energization of relay 401, at springs 430, 431 and 432 prepares the impulsing and change over circuits so that the relays 201 30 to 205 inclusive control the sending of vertical impulses to the finder through the second half of the banks of counting switch CS2. The circuit of the vertical magnet is then closed, being traceable from grounded 35 spring 471 through the normally closed contacts controlled by armature 468, conductor 473, springs 432, conductor 382, through wipers 225 and the multiple contacts connected thereto, conductor 378, springs 430, 40 and thence over the previously traced path through conductor 474 to the vertical magnet of the finder. While the first five impulses are being sent no testing occurs, the vertical magnet circuit is as above traced. 45 When the counting switch S2 has taken its sixth step, bringing wiper 225 into engagement with the contact to which conductor 260 is connected, testing takes place through the springs of the level relays 201-205, as 50 before. Assume that the call is in the seventh level and relay 202 is energized, the sixth pulse will go through as before, and after the seventh pulse the switch over circuit will be completed and is traceable from 55 the ground in the control equipment CE2 previously traced to wiper 225, conductor 262, springs 230, conductor 265, conductor 380, springs 431, springs 458 and thence through the winding of the switch over relay 406, energizing that relay as before to transfer the impulsing circuit to the rotary magnet of the finder.

Assume now that all finders in group 2 are busy, responding to which conductor 477 60 loses its ground. The circuit for relay 404

is completed when the auxiliary start relay 409 restores, from ground through the break contact of spring 471, the upper winding of the relay 404, through resistance 472 to battery. Energizing that relay which at 70 springs 452 closes a circuit through the upper winding of relay 403, to battery to energize that relay to transfer the group 2 conductor 371 to the control equipment CE1 which is now assumed to be in readiness to 75 handle a call. If a calling line in group 2 originates a call at this time, one of the level relays, 207 for example, energizes and grounds the start conductor 371 which now traverses a circuit through spring 436 and 80 its make contact over conductor 370, through spring 350, springs 352, through the winding of start relay 309 to negative battery, to register the call in the group 1 control equipment CE1. Impulsing goes on as before, through the medium of the auxiliary start relay which is energized through springs 356 of the start relay 309. The counting switch CS1 is operated, under the control of relay 207, which is connected to 85 the latter half of the banks swept over by the wipers of VS1 and the line appears in the seventh level of the group 1 finders. The impulsing circuit of the vertical magnet may be traced from ground through springs 90 327, normally closed springs controlled by armature 330, conductor 393 through springs 362, conductor 273, wiper 220, multiple contacts connected thereto, conductor 377, springs 367, thence through the previously 95 traced circuit through conductor 394 to the vertical magnet of the finder F. The first seven impulses are delivered over this circuit without change, at which time wiper 220 is in engagement with bank contact to which 100 conductor 269 is connected, completing a circuit through that conductor, springs 241, conductor 379, springs 361, conductor 395, springs 338 and thence through the upper winding of the switch over relay 304 to battery. Relay 304 energizes to transfer the 105 impulsing circuit to the rotary magnet of the finder, as has been hereinbefore explained. 110

Thus it will be seen that through the 115 medium of the two start relays 308 and 309, lines in either group can start the control equipment CE1 to control the finders of the first group to pick up a call, the relay 308 starting a group 1 call in the control equipment 1 and the relay 309 starting a group 2 call therein. Similarly relays 401 and 402 start control equipment 2, 401 serving group 1 and 402 serving group 2. Control equipment CE1 is provided with a key comprising springs 344 through which the switchroom attendant may throw that control equipment out of service for repairs and adjustment, that key serving to energize 120 relay 306 through its lower winding. The 125 130

relay 306 on energizing, closes the circuit for relay 307 as before to switch the start wire 277 over to the other control equipment. Similarly, control equipment CE2 is provided with a key comprising springs 454 which when operated energize relay 404 to close a circuit for relay 403 and connect start 371 to control equipment CE1.

10 *Abandoned calls.*

From the foregoing description it will be apparent that when once started the control equipment CE1 and CE2 go through a cycle of operation independent of the calling subscriber's loop. It may happen that after the control equipment has been started the subscriber will abandon the call, that is replace his receiver on the switchhook, whereupon his line relay, such as 2, will be deenergized 20 and the battery potential will be removed from the private contacts, such as 76'. The finder will step up to the proper level as before, start testing in the level for the marked contact, which is non-existent at 25 this time, and therefore the finder will take eleven rotary steps, the eleventh step closing the cam springs 38, which upon closing complete a circuit from ground through those springs on conductor 74 to the upper winding of switch through relay 302, energizing that relay to switch through the control equipment and finder, the finder releases immediately because the line relay 7 restores and opens circuit of the release relay 8 permitting that relay to restore and remove ground from the release trunk conductor. The control equipment CE1 releases to normal in the usual manner, and the finder allotter FA1 preselects another finder in 40 readiness for the next call.

Revertive pulse fails.

If for some reason or other the vertical or rotary magnets of the finder F fail to 45 return ground over the revertive conductor 77, impulse relay 303 will not be energized, and after a brief interval slow-to-pull up relay 305 will energize, and at springs 343 close a circuit for the impulse relay 303 50 which energizes to terminate the impulse. If the failure to return the revertive pulse is due to a dirty contact, the finder switch may be successfully operated at a slower rate of speed by the auxiliary repulse relay 55 305, in which case the impulses to the vertical and rotary magnets are long enough to insure their full operation. If, however, the magnet is faulty and cannot completely energize, five impulses are sent to it, and the counting switch VS1 encounters the sixth contact 60 and the finder is switched over and rotated on its normal level to the eleventh rotary position, whereupon cam springs 38 operate and switch through the finder as hereinbefore explained. Thus it will be seen that the

control equipment when once started, will go through a cycle of operations, attempting to place the finder upon the contacts of the calling line if possible, and if impossible, will release the faulty finder to permit the allotter FA1 to pick out another finder to handle the call.

While I have chosen to show my invention in connection with a particular type of system, employing a particular type of apparatus, I have done so by way of example only, as there are many adaptations and modifications which can be made by one skilled in the art, without departing from the scope of the invention, I am not to be limited by the specific disclosure made.

Having thus described my invention what I consider new and desire to have protected by Letters Patent is pointed out in the appended claims.

85 What is claimed is:

1. In a telephone system, a group of lines, a plurality of groups of finder switches having access thereto, said lines being divided into subgroups each of which is first choice to one of said groups of finders, and means responsive to the initiation of a call on any line for starting and directly controlling a finder switch in the group to which the subgroup containing said line is first choice.

2. In a telephone system, a subscriber's line, two finder switches having access to said line, and means responsive to a call on said line to start one or the other of said finders, one of the finders when operated being controlled by one digit to find said line, and the other finder when operated being controlled by another digit to find said line.

3. In a telephone system, a subscriber's line, two finder switches having access to said line, a control equipment for each finder, means responsive to the initiation of a call on said line to register separate numbers representing said line in said control equipments, and means controlled by said first means under normal condition for starting the finder in whose control equipment the lower number is registered to find the line, said last means under certain other conditions starting said other finder to find the line.

4. In a telephone system, a line, a pair of finder switches having access thereto, said line being an early choice to one finder and a later choice for the other finder, means responsive to the initiation of a call for normally directly controlling the early choice finder to find said line and for starting the later choice finder under certain other conditions to find the line.

5. In a telephone system, a line, a group of finder switches having access thereto, means responsive to the initiation of a call from said line to register two different digits, and means responsive to conditions in

the finder switch group to operate a finder of said group in accordance with one digit to find the line, and under other conditions to operate a finder of the group in response to the other digit to find the line.

6. In a telephone system, a group of lines, two groups of finder switches having access to said group of lines, certain of said lines appearing in the first half of the banks of the first of said finder groups and in the second half of the banks of the second of said finder groups, other of said lines appearing in the first half of the banks of said second finder group and in the second half of the bank of the first finder group, and means responsive to the initiation of a call on any of said lines for preparing a control circuit to each of the said finder groups and for starting a finder switch in the group in which said calling line appears in the first half of the bank to establish a connection with said line.

7. In a telephone system, a group of lines, two groups of finder switches having access to said group of lines, certain of said lines appearing in the first half of the banks of the first of said finder groups and in the second half of the banks of the second of said finder groups, other said lines appearing in the first half of the banks of said second finder group and in the second half of the bank of the first finder group, and means responsive to the initiation of a call on one of said lines for preparing a control circuit to each of the said finder groups and for starting a finder in the group in which said line appears in the second half of the banks, if all of said finders of the other group are busy.

8. In a telephone system, two groups of subscribers' lines each divided into a plurality of subgroups, a finder switch mechanism having access to said group of lines, means responsive to the initiation of a call on one of said lines to start that finder switch, means for directly moving said finder switch to the subgroup containing the calling line, and means in said finder switch for simultaneously testing for said calling line in the subgroup containing it and in the corresponding subgroup of the other of said groups of lines.

9. In a telephone system, two groups of subscribers' lines each divided into a plurality of subgroups, a finder switch mechanism having access to said group of lines, means responsive to the initiation of a call on one of said lines to start that finder switch, means for directly moving said finder switch to the subgroup containing the calling line, and means including a test relay and circuit therefor for simultaneously testing in the selected subgroup and in the corresponding subgroup of the other line group in search of said calling line.

10. In a telephone system, a two coordinate finder switch, two groups of subscribers' lines, each divided into subgroups in accordance with the primary movement of said finder switch, a control mechanism responsive to the initiation of a call on one of said lines to move said finder in a primary direction to the subgroup containing said calling line, means also responsive to the initiation of said call for marking the contact of said subgroup associated with said line in a distinctive manner, wipers on said finder switch, means for then moving said switch in a secondary motion to bring certain of said wipers into engagement with contacts of the group containing the contacts marked by said calling line, and means in said finder switch for simultaneously testing the contacts of the group containing the calling line and of the corresponding subgroup of the other line group in search of said marked contact, and means responsive to the establishment of a circuit through said finder and said marked contact for stopping said finder and for returning said common equipment to its normal position.

11. In combination with a group of finder switches which are directly controlled, a line accessible to said finders, said line being an early choice to certain of said finders and a later choice to others of said finders, and means responsive to the initiation of a call for normally starting one of the early choice finders to find said line and for starting one of the later choice finders under certain other conditions to find the line.

12. In a telephone system, a group of lines, a group of finder switches having access to said lines, control equipment for said finders, means responsive to the initiation of a call on one of said lines for registering two numbers indicative of said line in said control equipment, and means in said control equipment responsive to said registration for directing one of said finders to said line under the control of one or the other of said registered numbers.

13. The combination of a group of two directional finder switches which are directly operated during their primary movement by a means external to the finders and which select a particular contact by their secondary movement under the control of devices in the finders themselves, and a group of lines each line of which is an early choice to certain of said finders and a later choice to others, and means responsive to the initiation of a call on one of said lines for preparing control circuits to both the early and late choice finders and for starting the early choice finder if it be idle.

14. In a telephone system, a group of lines divided into sub groups, two finder switches having access to said lines, said subgroups appearing as an early choice to the

first of said finders and as a later choice to the other of said finders, a register relay for each of said subgroups, a control equipment for each of said finders, means responsive to the initiation of a call on one of said lines for energizing the register relay of the subgroup containing that line, means controlled by said register relay for registering a different digit in said control equipments, 5 means also controlled by said register relay for starting the early choice finder if it is available or the later choice finder if the former is not available and for transmitting the digit registered in the control equipment of 10 the selected finder to that finder, and means in said finder responsive to said digit for selecting said subgroup and for searching for said calling line therein.

15. In a telephone system, a finder switch, 20 an operating magnet in said finder, means for closing a circuit to said operating magnet to energize it, a pulse ending relay, means controlled by said operating magnet in its energized position for energizing said pulse ending relay to open the circuit of said operating magnet, two test relays in 25 said finder, means also controlled by said pulse end relay for extending a circuit through said test relays in multiple and said pulse ending relay in series therewith, and means for energizing one or the other of said test relays over said circuit, said means locking said pulse ending relay energized to stop 30 said finder.

35. 16. In a telephone system, a finder switch containing an operating magnet, two test relays, and two test wipers; a control equipment including means for closing a circuit to said operating magnet to energize it, a pulse ending relay in said control equipment, means controlled by said operating magnet in its energized position for energizing said pulse ending relay to open the circuit of said operating magnet, a switch through relay in 40

45 said control equipment, means also controlled by said pulse ending for extending a circuit through said pulse ending and switch through relays in series thence through parallel paths each including a test relay and a test wiper in series, means for energizing one 50 or the other of said test relays over said circuit, said means also locking said pulse ending relay energized to stop said finder and energizing said switch through relay, and means controlled by said switch through relay for disengaging said control equipment from said finder.

17. In a telephone system, a finder switch containing an operating magnet, two test relays and two test wipers, two groups of subscribers' lines, a test contact for each line accessible to the test wiper associated with that group, a control equipment associated with said finder, means in said control equipment responsive to the initiation of a call for closing a circuit to said operating magnet to energize it, means controlled by said operating magnet for energizing said pulse ending relay to open the circuit of said operating magnet, a switch through relay in said control equipment, means also controlled by said pulse ending relay for extending a circuit through said pulse ending relay, said switch through relay, thence through parallel paths each including a test relay and its associated 70 test wiper and the test contact engaged thereby, and means associated with the test contact of the calling line for energizing the test relay, whose wiper engages that contact over said circuit to establish a connection between the finder and the line, and for maintaining said pulse ending relay energized to stop the finder and for energizing said switch through relay to disassociate said control equipment from said finder.

In witness whereof, I hereunto subscribe my name this third day of May, A. D. 1927.

RUDOLPH F. STEHLIK.
